UNITED STATES PATENT OFFICE.

EDWARD B. GALLAHER, OF NEW YORK, N. Y., ASSIGNOR, BY MESNE ASSIGNMENTS, TO THE PNEUMATIC SUPPLY AND EQUIPMENT COMPANY, OF NEW YORK.

DESIGN FOR A FRAME FOR BELTED COMPRESSORS.

SPECIFICATION forming part of Design No. 32,216, dated February 13, 1900.

Application filed November 11, 1899. Serial No. 736,700. Term of patent 3½ years.

To all whom it may concern:

Be it known that I, EDWARD B. GALLAHER, a citizen of the United States, and a resident of New York, in the county of New York and State of New York, have invented a certain new and original Design for a Frame for a Belted Compressor, of which the following is a specification.

Referring to the drawings, Figures 1 and 2 represent, respectively, side and front elevations of my frame for a belted compressor.

My design consists of the vertically-inverted water-jacketed cylinder A, supporting the pedestal-bearings B and mounted on the base C.

The leading features of my design are the

overhanging pedestal-bearings B, in combination with the inverted vertical cylinder mounted on the base, as shown.

Having described and shown my invention, I claim as new and desire to secure by Letters Patent—

The design for a frame for a belted compressor as herein shown and described.

Signed at New York, in the county of New York and State of New York, this 31st day of March, A. D. 1899.

EDWARD B. GALLAHER.
